PRECAST PICKET FENCE

Milton W. Fisher and Edward G. Fisher,
Miami, Fla.

Application August 27, 1951, Serial No. 243,778

1 Claim. (Cl. 256—19)

1

This invention relates to new and useful improvements in fence structures and the primary object of the present invention is to provide a precast reinforced concrete fence composed of parts that are quickly and readily assembled in a convenient manner.

Another object of the present invention is to provide a precast reinforced concrete picket fence involving posts, rails and pickets that are interconnected by a novel and improved means in order to form a rigid and permanent fence structure.

A further object of the present invention is to provide a fence structure of the aforementioned character wherein the various parts thereof are heavily coated with a paint so that the interconnected parts of the fence structure will be firmly secured together.

A still further aim of the present invention is to provide a fence structure that is simple and practical in construction, strong and reliable in use, neat and attractive in appearance, inexpensive to manufacture and install, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary elevational view of the present invention assembled;

Figure 2 is an enlarged vertical sectional view taken substantially on the plane of section line 2—2 of Figure 1;

Figure 3 is an enlarged detail horizontal sectional view taken substantially on the plane of section line 3—3 of Figure 1;

Figure 4 is a perspective view of one of the upper rails used in the invention;

Figure 5 is a perspective view of one of the lower rails used in the invention;

Figure 6 is a perspective view of one of the posts used in the invention;

Figure 7 is a perspective view of one of the pickets used in the invention;

Figure 8 is a perspective view of another type of picket adapted to be used with the rails of Figures 4 and 5; and,

Figure 9 is a perspective view of a modified picket adapted to be used with the rails of Figures 4 and 5.

Referring now to the drawings in detail, wherein for the purpose of illustration, there is dis-

2

closed a preferred embodiment of the present invention, the numeral 10 represents the precast, reinforced concrete fence structure generally that is composed of a plurality of concrete posts 12 having central reinforcing rods 14 and flat vertical side faces 16 that are provided with inwardly tapered upper and lower horizontal recesses or rail seats 18 and 20.

The posts 12 are so arranged that the recesses 18 and 20 in one side face of one post will oppose or face the recesses 18 and 20 in one side face of an adjacent post. The tapered ends 22 of upper concrete rails 24 are seated in the opposing recesses 18 of the adjacent posts and the tapered ends 26 of lower concrete rails or curbs 28 are seated in the opposing recesses 20 of the adjacent posts. The upper rails 24 are relatively thin and they are each reinforced by a pair of rods 30 whereas the lower rails 28 are reinforced by central rods 32.

The rails 24 are each provided with a series or plurality of longitudinally spaced openings 34 that register with a series of longitudinally spaced downwardly and inwardly tapered recesses 36 in the upper face of each lower rail 28.

Concrete pickets 38 extend vertically between the upper and lower rails. The upper ends of the pickets 38 project upwardly through the openings 34 and the lower tapered ends 40 of the pickets 38 are seated in the recesses 36. Each picket 38 is reinforced by a central rod 42.

Pickets having various shaped upper ends may be employed. Whereas the pickets 28 have inclined upper ends 44 they may be replaced by pickets of the type shown in Figures 8 and 9. The picket 46 is constructed of concrete and includes a central reinforcing rod and tapered upper and lower ends 48 and 50. The picket 52, of Figure 9, is likewise provided with a central reinforcing rod, a tapered lower end 54 and a convexed upper edge 56.

In practical use of the present invention, the lower ends of the posts 12 are embedded in footings F with the ends of the upper and lower rails seated in the recesses 18 and 20. The pickets are then extended through the openings 34 until the lower ends of the pickets seat in the recesses 36. Then, the posts, rails and pickets are heavily coated with a suitable paint P which will enter the recesses 18, 20, 36 and the openings 34 to anchor and hold the pickets and rails together and the rails to the posts.

Having described the invention, what is claimed as new is:

55 A fence structure comprising a plurality of

spaced posts having side faces with the side face of one post opposing the side face of an adjacent post, each of said side faces having an inwardly tapered upper recess and an inwardly tapered lower recess, upper and lower rails connecting adjacent posts together, said upper rail having tapered ends secured in the upper opposing recesses of the two posts it joins, said lower rail having tapered ends secured in the lower opposing recesses of the two posts it joins, said upper rail having a plurality of longitudinally spaced openings therein, a plurality of spaced parallel pickets extending upwardly through the openings and having lower ends secured to the lower rail, said lower rail having a plurality of longitudinally spaced downwardly and inwardly tapered recesses therein, said pickets having tapered lower

ends secured in said plurality of recesses, and a paint covering the pickets, rails and posts and entering the recesses and openings to secure the rails to the posts and the pickets to the rails.

MILTON W. FISHER.
EDWARD G. FISHER.
